ABSTRACT: Metal is cast onto a body within a die cavity having preformed areas of relatively small size into which metal may be deposited. The metal, which is exterior of the die cavity after the metal within the cavity has solidified, is removed by shearing means.

APPARATUS FOR CASTING AND SHEARING
SOLIDIFIED SPRUES

In forming a transformer, die casting of the windings on the transformer core is desirable since this permits high volume production of transformers of very low manufacturing costs. In a previously suggested method and apparatus for casting a winding on a core to form a transformer, a further machining operation has been required after completion of the casting of the windings on the transformer core to remove the metal that does not form part of the windings of the transformer.

The present invention satisfactorily overcomes the foregoing problem by providing a method and apparatus in which the metal exterior of the cavity (this is the metal that does not form part of the windings of the transformer) is sheared from the metal within the cavity. Thus, the method and apparatus of the present invention eliminates the requirement for the additional machining operation of removing the extra metal from the windings of the transformer.

In forming integrated circuit modules, substrates, which have semiconductor chips mounted thereon, are supported on cards, which have integrated circuits formed therein. The modules include one or more substrates mounted in spaced relation to the card with pins being utilized to connect the chips and circuit lines on each of the substrates to circuits, which have been formed on the card.

Because of the miniature size of the module, the number of solid pins that may be inserted into the substrate is limited. Since the material of the substrate shrinks in a variable manner when it is subjected to sintering heat after the passages have been formed in the substrates during the compacting of alumina and glass powders, the solid pins, which must be on fixed center spacings, may not be aligned with the passages whereby the insertion of the solid pin into a misaligned passage may tend to fracture the substrate. If the spacing of the passages is not limited, the substrate would fracture easily because of the small space between the passages when a misalignment existed between a solid pin and a passage in the substrate. Furthermore, the insertion of the solid pins into the passages in the substrate requires a plurality of different operations resulting in relatively high labor costs and a relatively long period of assembly time.

The present invention satisfactorily solves the foregoing problem by providing a method and apparatus for forming pins by casting liquid phase metal into the passages in the substrate in a single operation. Thus, the present invention reduces both the labor and time required to produce substrates having interstitial pins, stacking pins, and card pins. Interstitial pins connect circuit lines, which are simultaneously formed on opposite surfaces of the substrate together with the pins, to each, other. Card pins are mounted on the substrate and disposed in holes in the card to mount the substrate on the card. Stacking pins are utilized to stack one substrate above the other and to connect the circuit lines on the two substrates. The card pins connect the circuits on the card with the circuit lines on the substrate having the card pins.

While the prior available mechanisms utilized separate devices for forming the interstitial pins, the stacking pins in the substrate, and the circuit lines on the top and bottom surfaces of the substrate, the present invention die casts all of these pins and circuit lines simultaneously. Thus, substantial savings in time and labor saving are obtained from the present invention.

In forming the card pins on the substrates, it has previously been necessary to form the four corner card pins with standoffs to insure a desired spaced relation between the card and the substrate. By utilizing the casting method and apparatus of the present invention, the standoffs on the corner pins may be formed simultaneously with the formation of all of the card pins, the interstitial pins, the stacking pins, and the circuit lines.

Circuit lines and pattern fingers are presently formed on the surface of the substrate by screening and tinning. However, this method of forming circuit lines and pattern fingers on the surface of a substrate limits the number of circuit lines or pat-

tern fingers. Thus, as the circuit line and/or pattern finger density on the substrate increases, the distance between the circuit lines and/or pattern fingers decreases. Therefore, the number of circuit lines and/or pattern fingers that may be presented on a substrate surface are limited when utilizing the presently available screening and tinning equipment.

The present invention overcomes the problem of the screening and tinning equipment by casting and bonding the pattern fingers and circuit lines on the surfaces of the substrate. Thus, by casting and bonding the circuit lines and the pattern fingers on the surface of the substrate, the pattern fingers may be disposed very close to each other while still obtaining the desired spaced relation therebetween to permit each pattern finger to contact one of the balls or pads on a chip.

With the present invention, microcast products are produced. By this, it is meant that elements of very small size are die cast. For example, electrical conductor windings on miniature pulse transformer cores, which have an outside diameter of 0.230 inch, an inside diameter of 0.110 inch, and a thickness of 0.070 inch, may be microcast by the present invention with the windings having cross sections as small as 0.004 inch wide by 0.006 inch thick on 0.008 inch center distance spacings. Likewise, electrical conductor lines on substrates may be cast with a size of 0.004 inch wide by 0.002 inch thick on 0.007 inch center distance spacings.

In comparison, commercial die castings require wall sections from 0.060 inch thick to 0.600 inch. Thus, microcastings of the present invention may be considered as producing elements, which are 10 to 100 times smaller than are presently available from die casting equipment.

An object of this invention is to provide a casting method and apparatus in which the formed casting is sheared from the supplied metal.

Another object of this invention is to provide a method and apparatus for casting windings on a core to form a transformer.

A further object of this invention is to provide casting of the metallic elements of a substrate.

Still another object of this invention is to provide a method and apparatus for casting elements of very small size on a body.

A still further object of this invention is to provide a method and apparatus for casting and bonding circuit lines on a substrate.

The foregoing and other objects, features, and advantages of the invention will be more apparent from the following more particular description of the preferred embodiments of the invention as illustrated in the accompanying drawings.

In the drawings:

FIG. 1 is a top plan view of a transformer core having grooves into which windings are to be cast by the present invention.

FIG. 2 is a sectional view, partly in elevation, of the transformer core of FIG. 1 and taken along line 2-2 of FIG. 1.

FIG. 3 is a perspective view of a portion of transformer formed by windings cast by the present invention on a core.

FIGS. 4-9 are schematic views illustrating the relationship between the parts of the apparatus of FIG. 10 and the metal injector nozzle during casting of the windings on the core.

FIG. 10 is a sectional view of a portion of a casting apparatus in which the core of FIG. 1 is disposed for having the windings cast therein.

FIGS. 11-16 are sectional views illustrating the relationship of parts of the apparatus of FIG. 10 during various steps in casting the windings on the core.

FIG. 17 is a fragmentary sectional view of a portion of a substrate having pins cast therein by the method of the present invention.

FIG. 18 is a fragmentary top plan view of a portion of the substrate of FIG. 17 and taken along line 18-18 of FIG. 17.

FIG. 19 is a fragmentary bottom plan view of a portion of the substrate of FIG. 17 and taken along line 19-19 of FIG.

FIG. 20 is a fragmentary sectional view illustrating the substrate of FIG. 17 having another substrate, which has had its pins cast therein, stacked thereon.

FIG. 21 is a fragmentary sectional view of a substrate having pins cast therein by the method of the present invention in which a second substrate is stacked on the first substrate and two castings are required to form one of the pins.

FIG. 22 is a fragmentary sectional view of a substrate having its pins cast therein by the method of the present invention with two sequential casting operations required to form heads of different height and the higher one supporting the pulse transformer of FIG. 3 thereon in stacked relation.

FIG. 23 is a sectional view of a substrate having pins and a heat sink cast therein by the method of the present invention.

FIGS. 24-26 are sectional views of a portion of a substrate and schematically illustrating the steps of a method in the casting and bonding of a circuit line thereon.

FIGS. 27-30 are sectional views of a portion of a substrate and schematically illustrating the steps of another method of casting and bonding a circuit line on the substrate.

FIG. 31 is a top plan view of a portion of a substrate having a plurality of pattern fingers cast and bonded thereon by the present invention.

FIG. 32 is an enlarged fragmentary top plan view of a portion of the substrate of FIG. 36.

FIG. 33 is a side elevational view of the portion of the substrate of FIG. 32.

FIG. 34 is a sectional view of a portion of the substrate of FIG. 32 and taken along line 34-34 of FIG. 32.

FIG. 35 is a sectional view of another portion of the substrate of FIG. 32 and taken along line 35-35 of FIG. 32.

FIG. 36 is a top plan view of a substrate having pins, circuit lines, and pattern fingers cast therein by the present invention.

FIG. 37 is a sectional view of a portion of the substrate of FIG. 38 and taken along line 37-37 of FIG. 38.

FIG. 38 is a top plan view of a portion of substrate having pins cast therein with circuit lines and pattern fingers simultaneously cast and bonded thereon by the present invention.

FIG. 39 is a bottom plan view of the substrate of FIG. 37.

FIG. 40 is a sectional view of a portion of the substrate of FIG. 41 and taken along line 40-40 of FIG. 41.

FIG. 41 is a top plan view of a portion of another form of a substrate in which pins, circuit lines, and pattern fingers are cast and bonded on the surface of the substrate by the present invention.

FIG. 42 is a bottom plan view of the portion of the substrate of FIG. 40.

FIG. 43 is a top plan view of a substrate having pins and circuit lines simultaneously cast and bonded thereon by the apparatus of FIGS. 45-52.

FIG. 44 is a sectional view of the substrate of FIG. 43 and taken along line 44-44 of FIG. 43.

FIGS. 45-52 are sectional views illustrating the relationship of various parts of a casting apparatus in forming pins and bonding circuit lines on a substrate.

FIG. 53 is a sectional view showing another form of cavity for casting windings on a core to form a transformer.

FIG. 54 is a sectional view of another type of cavity for casting windings on a core to form a transformer.

FIG. 55 is a schematic perspective view of the apparatus of FIGS. 45-52 for casting pins in the substrate and casting and bonding circuit lines on the substrate.

FIG. 56 is a timing diagram illustrating the relationships of the casting apparatus of FIGS. 45-52 at various times during a complete casting cycle.

FIG. 57 is a horizontal sectional view, partly in plan, showing the various cams and other mechanisms for correlating the movement of various elements of the casting apparatus of FIGS. 45-52 and corresponding to the position of the casting apparatus in FIG. 45.

FIG. 58 is a perspective view illustrating the connection between a cam positioned lever and a shaft of the load arm for loading the substrates in the casting apparatus of FIGS. 45-52.

FIG. 59 is a schematic horizontal sectional view showing the relationship of various elements of the casting apparatus of FIGS. 45-52 with the elements disposed in a position corresponding to the position between FIGS. 49 and 50.

FIG. 60 is a front elevational view, partly in section, of a portion of the die block assembly of the casting apparatus of FIGS. 45-52 on which the substrates are supported.

FIG. 61 is a sectional view of a portion of the die block assembly of FIG. 60 and taken along line 61-61 of FIG. 60.

FIG. 62 is an elevational view, partly in section, showing the driving arrangement between the drive shaft and the crankshaft for moving the die block assemblies relative to each other and taken along line 62-62 of FIG. 57.

FIG. 63 is an elevational view, partly in section, of a cam and its connecting linkage for moving the load arm shaft and taken along line 63-63 of FIG. 57.

Referring to the drawings and particularly FIGS. 1 and 2, there is shown a transformer core 10, which is encapsulated by enclosing it within a plastic 11. The plastic 11 has grooves 12 formed therein to receive metal to form windings on the core 10. As shown in FIG. 3, metal has been disposed within the grooves 12 in the plastic 11 to form a pulse transformer. A bifilar winding is shown with the two windings electrically insulated from each other and the core by the plastic 11.

Electrically conductive windings may be simultaneously cast on three cores as described in the modifications of the apparatus of FIGS. 45-52, but operations for only one core are described below.

30 The encapsulated core 10, which is preheated, is adapted to be disposed within a preheated cavity, which is formed by die blocks 14 and 15 (see FIG. 10). The core 10 is supported on a preheated tapered hollow tube 16, which is mounted in the die block 14. Only the portion of the tube 16 exterior of the die block 14 is tapered. The preheating of the core 10 and the die members is preferably accomplished in an atmosphere of inert or reducing gas. The die members are individually preheated and individually controlled by electrical means (not shown).

35 The preheated core 10 is mounted on the tube 16 by a load arm 16' as shown in FIG. 5. The load arm 16' is mounted for rotating and axial movement as described for the load arm in the modification of FIGS. 45-52 to properly position the core 10 with respect to the tube 16 during movement of the core 10 onto the tube 16.

40 45 The interior of the hollow tube 16 has a cylindrical passage 17 therein within which is disposed a shearing member 18. The shearing member 18 has a cylindrical portion 19 disposed within the passage 17 and an enlarged flange 20 abutting against the end of the tube 16. A conical shaped head 21 extends from the flange 20.

45 50 The die block 15 has a die recess or cavity 22 formed therein on one side thereof to receive the core 10 when the die block 14 is moved into engagement with the die block 15 as shown in FIGS. 6 and 11. The die cavity 22 communicates through a passage 23 to the opposite side of the die block 15. The passage 23 permits liquid phase or molten metal to be supplied to the mold cavity, which is formed when the die blocks 14 and 15 are in engagement with each other.

55 60 As shown in FIG. 11, the passage 23 communicates with the grooves 12 in the encapsulating plastic 11 of the core 10 by means of a gate opening 24, which is formed between the flange 20 of the shearing member 18 and a wall of the die block 15. Thus, when liquid phase metal is supplied through the passage 23, it flows into the grooves 12 by means of the gate opening 24.

65 70 After the die blocks 14 and 15 have been disposed adjacent each other with die blocks 25 and 26 adjacent the die block 15 through moving the die block 14 to the right, the die blocks 14, 15, 25, and 26 will be moved toward an injection nozzle 27 (see FIGS. 6 and 11), which has a passage 28 formed therein to supply liquid phase or molten metal to the passage 23 by means of a passage 29 in the die block 25, a passage 30 in the die block 26, and a passage 31 in a nozzle seat 32 in the die block 26.

The die block 15 has a vacuum runner cavity 124A formed therein by machining a groove in the die block 15. The vacuum runner cavity 124A is connected to a vacuum pump (not shown) through a port 126A in the die block 15, a fitting (not shown), a flexible hose (not shown), and a solenoid valve (not shown). The arrangement of the vacuum pump, the fitting, the flexible hose, and the solenoid valve is similar to the arrangement shown and described in detail with respect to the modification of FIG. 45. Accordingly, whenever the solenoid valve (not shown) is open, the vacuum pump (not shown) applies a vacuum to the runner cavity 124A.

When the movable die blocks 14, 15, 25, and 26 are disposed as shown in FIG. 7 with the injection nozzle 27 contacting the injection nozzle seat 32, the opening of the solenoid valve results in the evacuation of any gas from the vacuum runner cavity 124A in the die block 15. The die cavity 22 communicates with the vacuum runner cavity 124A through gas passageways, which are about 0.0002 inch deep, formed in the surface of the die block 15 between the die cavity 22 and the runner cavity 124A by machining. This evacuation also results in evacuating the passages 23, 29, 30, and 31 in the movable die blocks 15, 25, and 26 since they are in sealing contact with each other.

At the completion of the evacuation by the vacuum pump, the liquid phase metal is supplied under pressure through the passage 28 and the injection nozzle 27 by suitable means (not shown). One suitable means is shown and described in the modification of FIGS. 45-52.

When the liquid phase metal is supplied to the grooves 12, the metal continues to flow until the grooves 12 are completely filled. As long as the metal flows, the friction of the metal flowing prevents any solidifying of the metal. However, because the latent heat of melting of the metal is relatively low, the metal solidifies as soon as the grooves 12 have been completely filled. When this occurs, there is solidifying of the metal within the passages 23, 29, and 30, and there also is some solidifying of the metal within the passage 31 as shown in FIG. 12. The metal, which is still liquid when the supply of the metal under pressure to the passage 31 ceases, drains from the passage 31 into the passage 28 in the nozzle 27.

It should be understood that the amount of time to fill the grooves 12 is approximately 2 to 3 milliseconds. Thus, only a very short period of time is required to supply the metal.

The preheating of the core 10 and the die cavities in an inert or a reducing gas atmosphere prevents the premature solidification of the metal and prevents oxidization of the metal during casting. The vacuum in the die cavities and the high pressure of metal injection prevents the entrapment of gas bubbles in the cast metal in the grooves 12.

Then, the die blocks 14, 15, 25, and 26 are moved simultaneously to the left away from the injection nozzle 27 as shown in FIG. 8. After movement of the die blocks 14, 15, 25 and 26 away from the injection nozzle 27, the die blocks 25 and 26 are moved vertically relative to the die block 15 as indicated by arrow 33 in FIG. 13. This results in the metal in the passage 29 being sheared from the metal in the passage 23.

Then, the die blocks 14, 15, and 25 are moved to the left away from the die block 26, which is prevented from moving further to the left, to the position FIG. 14. As a result of the movement of the die block 25 away from the die block 26, the die block 25 ceases to be engaged with a runner 34, which is retained in the die block 26 by hook ejector pins 35 (one shown) at the time that the die block 25 is moved to the left away from the die block 26.

With the die blocks 25 and 26 separated, the runner 34 is removed from the die block 26 by moving the hook ejector pins 35 to the left. This is accomplished by suitable means such as shown and described in the modification of FIGS. 45-52, for example. Then, a pressurized gas blast, indicated by arrows 36 and controlled by a solenoid valve (not shown), is directed to remove the runner 34 from the hook ejector pins 35 and direct the runner 34 to a collection area.

At the same time that the hook ejector pins 35 are advanced to the left, the shearing member 18 is advanced to the right. The movement of the shearing member 18 is controlled by suitable means such as one of the cams shown in FIG. 57. As a result, the metal, which is exterior of the die cavity within which the core 10 is disposed, is sheared from the metal within the cavity by the flange 20 of the shearing member 18.

Since the flange 20 cooperated to form the gate opening 24 into the cavity in which the core 10 was disposed, all of the metal, which is exterior of the cavity, is sheared from the metal, which forms windings 37 (see FIG. 3) on the core 10 whereby a transformer 38 is produced. As shown in FIG. 14, a body 39 of excess metal is pushed by the shearing member 18 through the passage 23 in the die block 25.

When the body 39 is pushed exterior of the die block 25, a pressurized gas blast, which is indicated by arrows 40 and controlled by a solenoid valve (not shown), is supplied from a suitable source of gas pressure to act on the body 39. As a result, the body 39 falls downwardly, as indicated in FIG. 14, to a collection area.

The gas blasts 36 and 40 are sources of the atmosphere of inert gas or reducing gas enveloping the die casting process of this invention. A suitable inert gas may be nitrogen or argon.

A suitable reducing gas may be a mixture of 4 percent hydrogen and 96 percent nitrogen or argon and is noncombustible in air.

The shearing member 18 is then returned into the tube 16 as shown in FIG. 15. The die block 14 is moved to the left away from the die blocks 15 and 25 as shown in FIGS. 9 and 15.

Then, the shearing member 18 and the tube 16 are retracted into the die block 14 as shown in FIG. 16 by the controlling cam. When there has been complete retraction of the tube 16 and the shearing member 18 into the die block 14, an unload arm 41 is disposed in surrounding relation to the transformer 38 and is adapted to retain the transformer 38 therein through application of a vacuum as indicated by arrows 42.

Then, the unload arm 41 is moved from its solid line position of FIG. 16 to the phantom line position at the same time that ejector pins 43, which are carried by the die block 14, are moved to the right as indicated by the arrows. The ejector pins 43 urge the transformer 38 into the pockets of the unload arm 41 to insure that the transformer 38 is properly positioned within the unload arm 41. The unload arm 41 then transports the transformer 38 to a collecting area.

The movements of the unload arm 41 would be similar to that described for the unload arm in the modification of FIGS. 45-52. Thus, the unload arm 41 both rotates and moves axially.

The ejector pins 43 could be actuated by any suitable means. For example, the ejector pins 43 could be mounted on a spring biased plate, which engages fixed studs to overcome the springs and cause the ejector pins 43 to move. This type of arrangement is shown and described more particularly in the modification of FIGS. 45-52.

By making the tube 16 tapered at its end, the retraction of the tube 16 into the die block 14 causes separation of the tube 16 from the windings 37. Of course, since the metal, which filled the grooves 12 to form the windings 37, shrank onto the tapered tube 16, there was no possibility of the transformer 38 not remaining on the tapered tube 16 when the die blocks 14 and 15 were separated from each other by movement of the die block 14 to the left.

If there should be any flashings between the windings 37 due to an interference fit not existing between the plastic 11 and the die block 15, the flashings may easily be removed by etching, for example. It is necessary for the flashings to be removed between the windings 37 or there would be a short circuit so that the transformer 38 would be inoperative.

Referring to FIG. 53, there is shown another form of the apparatus of the present invention for casting the windings 37 on the core 10 to form the transformer 38. The apparatus includes a die block 50 having a center core pin 51 mounted therein for sliding movement relative thereto. The center core

pin 51 is adapted to support the core 10 thereon and is tapered in the portion extending beyond the die block 50.

The die block 50 supports an annular ejector sleeve 52, which surrounds the center core pin 51. The die block 50 has a plurality of ejector pins 53 mounted therein. The ejector pins 53 are utilized to eject surplus metal after formation of the windings 37 is completed.

The core 10 is surrounded by a die block 54, which has an annular cavity 55 formed therein. The cavity 55 receives liquid phase or molten metal for supply to the grooves 12 in the plastic 11, which encapsulates the core 10.

An annular ejector sleeve 56, which has a slightly smaller diameter than the ejector sleeve 52, is disposed on the opposite side of the core 10 from the ejector sleeve 52 when casting of the windings 37 in the grooves 12 is occurring. The ejector sleeve 56 is supported in a die block 57, which abuts against portions of the die block 54.

The liquid phase metal is supplied to the cavity 55 in the die block 54 through a passage 58 in the die block 54. The passage 58 communicates with a passage 59 in an injection nozzle 60. Thus, when the die block 54 is disposed adjacent the injection nozzle 60 so that the passage 59 communicates with the passage 58, liquid phase metal under pressure is supplied to the cavity 55.

The die block 54 has gate openings 61, which are equal in number to the grooves 12 in the plastic 11 and are aligned with the grooves 12, for communication from the cavity 55 into the cavity within which the core 10 is disposed. The cavity is formed by the ejector sleeves 52 and 56, the die block 54, and the center core pin 51.

Additionally, the position of the center core pin 51 is such that liquid phase or molten metal may escape from the mold cavity into a passage within the ejector sleeve 56 through overflow openings 62, which are equal in number to the grooves 12 and are aligned with the grooves 12 in the plastic 11. The passage in the ejector sleeve 56 has a shearing insert 63 therein with an enlarged area 64 adjacent the overflow openings 62.

The enlarged area 64 accommodates the overflow of the liquid phase metal to clear any residual entrapped gas that might be within the mold cavity containing the core 10. A pin 65, which is slidably disposed within the insert 63, is employed to remove the metal in the area 64 after die casting of the windings 37 is completed.

After the molten metal has solidified to form the windings 37 in the grooves 12, the center core pin 51 and the shearing insert 63 are moved to the left only a distance sufficient to shear the metal at the overflow openings 62. Thus, this shears only the metal exterior of the mold cavity.

Following the movement of the center core pin 51 and the shearing insert 63 to the left, the ejector sleeve 52, the pulse transformer 38, and the sleeve 56 are moved to the left with the continuing leftward motion of the center core pin 51 while the die blocks 50, 54, and 57 and the shearing insert 63 remain stationary. Consequently, the leftward movement of the pulse transformer 38 relative to the stationary die block 50 and the metal feed gate openings 61 shears the metal in the grooves 12 of the pulse transformer 38 free from the metal in the metal feed gate openings 61. Thus, this shears only the metal exterior of the mold cavity.

The sheared metal within the enlarged area 64 is retained within the shearing element 63. The sheared metal within the annular cavity 55 is retained between the die blocks 50 and 54, which are in sealing engagement. As a result, all the metal, which was exterior of the mold cavity, is removed.

After the shearing of the metal at the gate openings 61 has been completed, the pulse transformer 38 is retained on the center core pin 51 and against the ejector sleeve 52 by the ejector sleeve 56. This is shown in phantom lines in FIG. 53.

All of the apparatus elements shown in FIG. 53 except the injection nozzle 60 are now moved to the left to provide a small separation from the nozzle 60 and unsolidified metal drains back into the nozzle 60. Then, the die block 50, the

sleeve 52, the core pin 51, the pulse transformer 38, the ejector pins 65, and ejector pins 66, which are slidably mounted in the die blocks 54 and 57, continue to move to the left while the die blocks 54 and 57 and the sleeve 56 remain stationary. The leftward motion of the ejector pins 65 and 66 stops when their left ends are vertically in line with the left (phantom) end of the sleeve 56, which is now stationary. As a result, the metal in the annular cavity 55 and within the shearing insert 63 is ejected by the ejector pins 66 and 65, respectively, and is free to fall through the widening space between the right face of the leftward moving die block 50 and the left (phantom) end of the sleeve 56, which is now stationary.

The center core pin 51, the sleeve 52, the pulse transformer

38, the die block 50, and the ejector pins 53 continue to move to the left until there is sufficient space between the right face of the die block 50 and the left end of the sleeve 56 for the ejected metal to fall free and clear. At this time, the leftward motion of the ejector pins 53 is first stopped; then, after an additional 0.010 inch of leftward motion, the die block 50 is stopped with the ejector pins 53 projecting 0.010 inch to the right of the right face of the die block 50.

The aforesaid 0.010 inch projection of the ejector pins 53 moves the sheared metal, which was in the annular cavity 55, free of the right face of the die block 50 so that a gas jet (not shown) may free the sheared metal from the ejector pins 53 to fall free and clear and be disposed. The gas jet (not shown) also assists in the disposal of the sheared metal that was ejected from within the shearing insert 63.

30 The center core pin 51, the sleeve 52, and the pulse transformer 38 continue to move to the left until there is sufficient space between the left face of the now stationary die block 50 and the right face of the sleeve 52 to permit unloading the pulse transformer 38 and loading another of the encapsulated cores 10. The apparatus elements used for unloading the pulse transformer 38 and loading the encapsulated core 10 are similar to the apparatus elements previously shown and described relative to FIGS. 9 and 16. The leftward motion of the sleeve 52 now stops while the center core pin 51 continues to move to the left until it is completely withdrawn into the now stationary sleeve 52; meanwhile, the unload arm 41 (see FIG. 16) has picked up the pulse transformer 38 and moves it to a collection chute (not shown) such as shown in FIG. 55. This completes the casting cycle.

45 The next casting cycle is initiated as the center core pin 51 starts to move to the right and is loaded with an encapsulated core 10 by a load arm 16' (see FIG. 5). The apparatus elements are progressively closed as the center core pin 51 continues to move to the right until they are in the relative positions of FIG. 53 with the die blocks 54 and 57 in contact with the injection nozzle 60. The sequence of the progressive closing is exactly the reverse of their opening during the leftward movement of the center core pin 51 as previously described.

55 The provisions for the inert or reducing gas atmosphere enveloping the die casting process and the preheating of the core and die members are similar to the provisions previously described relative to FIGS. 1-9.

Referring to FIG. 54, there is shown another apparatus for casting the windings 37 on the core 10. The apparatus of FIG. 54 includes a tapered center core pin 70, which is supported by a die block 71 and has only the portion extending beyond the die block 71 tapered. The center core pin 70 supports the core 10 thereon and forms one side of the mold cavity. An ejector sleeve 72 is slidably mounted on the center core pin 70 and forms another wall of the mold cavity within which the core 10 is disposed.

60 A die block 73 is disposed adjacent the die block 71 and defines another wall of the mold cavity within which the core 10 is disposed. As shown in FIG. 54, the die block 73 has one wall vertically aligned with the end of the center core pin 70.

An annular feeder member 74 is disposed adjacent the die block 73 during casting. The feeder member 74 has a cavity 75 formed therein to receive liquid phase or molten metal for supply to the cavity having the core 10 disposed therein.

The cavity 75 communicates with a passage 76 in a second feeder member 77. The metal is supplied to the passage 76 from a passage 78 in an injection nozzle 79. The passage 78 in the injection nozzle 79 is in communication with the passage 76 when liquid phase or molten metal is to be supplied to the mold cavity. The liquid phase metal is supplied under pressure by suitable means (not shown) such as those shown for the modification of FIGS. 45-52, for example, through the passage 78 in the injection nozzle 79.

The feeder member 74 has two series of gate openings 80 and 81 formed therein and arranged in concentric circles. The openings 80 and 81, which are 0.003 inch diameters at their smaller ends, communicate with the cavity 75 in the feeder member 74 and with the mold cavity within which the core 10 is disposed. The openings 80 and 81 are each equal in number to the grooves 12 in the plastic 11 and are aligned with the grooves 12.

Additionally, the feeder member 74 has gate openings 82 therein for communication with cavities 83, which are formed in the die block 73 and are in communication with the mold cavity and with the cavity 75 in the feeder member 74. Accordingly, liquid phase metal also flows through the gate openings 82 into the cavities 83 when the liquid phase metal is supplied to the cavity 75 for casting the windings 37 on the core 10. The gate openings 82 results in tabs 84 being formed as part of the windings 37.

After the injection nozzle 79 has supplied the liquid phase metal to the mold cavity and the cavities 83, the die blocks 71 and 73 and the feeder members 74 and 77 are moved to the left whereby the passage 78 in the injection nozzle 79 ceases to communicate with the passage 76. This does not occur until the metal within the cavity 75 has solidified due to the low latent heat of melting of the metal as previously mentioned. Some of the metal drains from the passage 76 into the nozzle passage 78 before solidification has occurred.

After the die blocks 71 and 73 and the feeder members 74 and 77 have moved to the left away from the injection nozzle 79, the feeder members 74 and 77 are moved vertically upward relative to the die blocks 71 and 73. As a result, the solidified metal is sheared at the exits of the gate openings 80, 81, and 82 so that all of the metal exterior of the mold cavity and the cavity 83 is sheared therefrom. This is accomplished by the upward movement of the feeder members 74 and 77. Then the die blocks 71 and 73 and the feeder member 74 move to the left while the feeder member 77 ceases to move. As a result, the metal, which is left within the cavity 75 and the gate openings 80-82 and forms a runner 85, is removed from the cavity 75.

The runner 85 is held by a hook ejector pin 88, which is slidably mounted in the second feeder member 77, after it is removed from the cavity 75. The feeder member 74 ceases to move to the left after there is sufficient space between the member 74 and the member 77 to allow the runner 85 to fall therebetween.

The runner 85 is removed from the hook ejector pin 88 by first moving the hook ejector pin 88 and ejector pins 89, which also are slidably mounted in the feeder member 77, to the left. A gas blast (not shown) then removes the runner 85 from the hook ejector pin 88.

After the member 74 stops moving, the die blocks 71 and 73 continue to move to the left. After the die blocks 71 and 73 have moved sufficiently to have sufficient distance between the die block 73 and the feeder member 74, the ejector sleeve 72 is stopped.

As a result of the ejector sleeve 72 stopping while the die blocks 71 and 73 continue to move to the left, the transformer 38, which has been formed through casting the windings 37 on the core 10, is removed from its support on the center core pin 70 of the die block 71. The transformer 38 may be grasped by the unload arm 41 or urged by pressurized gas to a collection area in the same manner as previously mentioned for the casting apparatus of FIGS. 10-16.

Referring to FIGS. 45-52, there is shown an apparatus for die casting pins and circuit lines on a plurality of substrates 100 simultaneously. Each of the substrates 100 may be formed of any suitable material that is nonconductive. One suitable example of the substrates 100 is formed of approximately 98 percent aluminum oxide and 2 percent glass. The substrates 100 have previously been formed with passages therein through which the pins are to extend.

One of the substrates 100 is shown in FIGS. 43 and 44 with interstitial pins 101, card pins 102, and circuit lines (not shown) having been cast thereon by the apparatus of FIGS. 45-52. The corner card pins 102 have standoffs 103 cast therein simultaneously.

As shown in FIG. 45, the die casting apparatus includes a plurality of die block assemblies, which are movable relative to each other and in which a plurality of the substrates 100 may be disposed simultaneously. Portions of the die block assemblies are individually preheated and individually temperature controlled by electrical means (not shown).

The apparatus includes a first movable die block assembly 104, which is slidably mounted on a pair of guide posts 105 (see FIGS. 57 and 59) and 106 (see FIGS. 55 and 57). The guide posts 105 and 106 are fixed to a die base 107, which is permanently attached to a vertically inclined member of a machine frame 108. The guide post 105 extends through one of the lower corners of the movable die block assembly 104 while the guidepost 106 extends through a diagonal upper corner of the assembly 104 as shown in FIG. 55.

The apparatus also includes a second movable die block assembly 109, which also is slidably supported on the guideposts 105 and 106 as shown in FIGS. 55, 57, and 59. A third movable die block assembly 110 also is slidably supported on the guideposts 105 and 106.

The third movable die block assembly 110 is slidably supported by extensions 111 and 112, respectively, of the guideposts 105 and 106. The extensions 111 and 12 are of a reduced diameter in comparison with the remainder of the guideposts 105 and 106 as shown in FIGS. 57 and 59.

The first movable die block assembly 104 includes a support member 113 (see FIG. 61) having three die sections 243, 244, and 245 (see FIG. 60) secured thereto by screws 246. The die sections 243, 244, and 245 have die inserts 247, 248, and 249, respectively, mounted therein with the die inserts 247-249 formed of hardened steel.

Each of the die inserts 247-249 has a layer 114 (see FIG. 45) of high-temperature plastic bonded thereto. The high temperature plastic has a thickness of 0.030 inch.

Accordingly, one of the substrates 100 may be disposed on the layer 114 of each of the die inserts 247-249. Thus, three of the substrates 100 may have metal cast thereon simultaneously.

The second movable die block assembly 109 includes a metal feed gate section 115 (see FIG. 45), three shearing sheets 116, and a layer 117 of a high-temperature plastic bonded to each of the sheets 116. The layer 117 of plastic has a thickness of approximately 0.030 inch, and each of the shearing sheets 116 may be formed of a suitable material such as molybdenum having a thickness of 0.005 inch.

The die block assemblies 104 and 109 cooperate together to form mold cavities for the three substrates 100. By forming the portions of the die block assemblies 104 and 109, which are adjacent each of the substrates 100 when they are disposed therebetween, of a material having adequate high-temperature characteristics to handle the molten or liquid phase metal and with a limited resiliency, any deviation in any of the substrates from flat and parallel surfaces is compensated for by the resiliency of the material of the layers 114 and 117 of plastic. Suitable examples of the materials of the layers 114 and 117 of plastic are high-temperature teflon, silicone, and polyimide plastics. The use of an atmosphere of inert or reducing gas in the die-casting process substantially increases the life of the preheated plastic mold cavities by avoiding adverse reactions between the plastics and the oxygen of air atmosphere.

Through utilizing the layers 114 and 117 of high-temperature plastic, the necessity for lapping each of the substrates 100 flat to eliminate any camber due to uneven shrinkage during sintering is eliminated. If the lapping process were not employed and only a hardened steel die cavity were used, the cambered surface of a substrate would not seal against the flat portions of the steel die cavities and liquid phase metal would escape to damage the equipment. Furthermore, the clamping of a cambered substrate between flat portions of a die cavity, which is formed in a hardened steel die, develops localized high stresses in the substrate at points of contact with the cavity to cause cracking and fracturing of the substrate and damage to the die cavity. By utilizing the layers 114 and 117 of high-temperature plastic, the layers not only seal against the substrates due to the limited resiliency of the plastic but also partially flatten the camber of the substrates without causing localized high stresses that would crack or fracture the substrates.

Each of the die inserts 247-249 of the die block assembly 104 has die cavities 118 therein to form the ends of the card pins 102. Each of the plastic layers 114 of the die block assembly 104 has cavities 119 therein to form the standoffs 103 and the portions of the card pins 102, which do not have standoffs thereon, adjacent each of the substrates 100. Each of the plastic layers 114 also has die cavities therein to form the underside circuit lines (not shown), which might be formed on the substrates 100.

Each of the plastic layers 117 of the die block assembly 109 has die cavities 120 formed therein to cast the heads of the pins 101 and 102. Each of the layers 117 also has die cavities therein to form circuit lines (not shown) on the upper surface of the substrates 100.

The resiliency of the layers 114 and 117 is sufficient that a seal is provided around each of the substrates 100 to prevent any of the liquid phase metal from escaping between each of the substrates 100 and either of the adjacent layers 114 and 117.

The third movable die block assembly 110 includes a vertically slideable die block 121 having an injection nozzle seat 122 formed therein with an injection port 123 to receive the liquid phase metal.

The die block 121 has a vacuum runner cavity 124 formed therein by machining a groove in the die block 121. The vacuum runner cavity 124 is connected to a vacuum pump 125 through a port 126 in the die block 121, a fitting 127, a flexible hose 128, and a solenoid valve 129. Accordingly, whenever the solenoid valve 129 is open, the vacuum pump 125 applies a vacuum to the vacuum runner cavity 124.

When the movable die block assemblies 104, 109, and 110 are disposed as shown in FIGS. 45 and 57 with an injection nozzle 130 contacting the injection nozzle seat 122, the opening of the solenoid valve 129 results in evacuation of any gas from the vacuum runner cavity 124, three vertical feed runner cavities 131, and a horizontal feed runner cavity 132, which connects the vertical feed runner cavities 131 to each other, in the die block 121. The vertical feed runner cavities 131 communicate with the vacuum runner cavity 124 through gas passageways, which are about 0.0002 inch deep, formed in the surface of the die block 121 between the vertical feed runner cavities 131 and the vacuum runner cavity 124 by machining. This evacuation also results in evacuating die cavities in the movable die block assemblies 104 and 109 since they are in sealing contact with each other.

At the completion of evacuation by the vacuum pump 125, liquid phase metal is supplied from a plunger chamber 133 and through the injection nozzle 130 to the injection port 123 in the die block 121 to supply the liquid phase metal to the evacuated areas. The injection port 123 is sealed from the inert or reducing gas atmosphere, which is contained within an enclosed housing 133' (see FIG. 57) and in which the apparatus is located, when the injection nozzle 130 engages the nozzle seat 122.

Liquid phase metal is forced from the plunger chamber 133 by downward movement of a metal injection plunger 134. The

plunger 134 is moved downwardly past a port 135, which provides communication from a heated melting pot 136 to the plunger chamber 133. The melting pot 136 is secured to the machine frame 108.

5 The movement of the plunger 134 is controlled by the position of a piston 137, which has its rod 138 connected to the upper end of the plunger 134. The piston 137 is slidably disposed within a cylinder 139, which is secured to the machine frame 108 and has pressurized air supplied thereto through one of a pair of hoses 140 and 141 and removed therefrom to the outside atmosphere through the other of the pair of the hoses 140 and 141. A four-way solenoid valve 142 controls the connection of one of the hoses 140 and 141 to a high-pressure air source through a conduit 143 and the other of the hoses 140 and 141 to the outside atmosphere.

10 The movement of the plunger 134 is such that the liquid phase metal flows through the injection nozzle 130 under a pressure of 600 pounds per square inch. This continues until all of the voids within the die block assemblies are filled. The liquid phase metal does not flow through the 0.0002 inch gas passageways between the vertical feed runner cavities 131 and the vacuum runner cavity 124 because the liquid phase metal solidifies against the surfaces of the metal feed gate section 115 and the die block 121 since they are substantially cooler than the melting point of the metal. The liquid phase metal chills and freezes within all of the voids in a few milliseconds.

15 After the metal has solidified, it is necessary to move the movable die block assemblies 104, 109, and 110 laterally relative to each other to permit removal of the three substrates 100 with the cast metal therein and removal of the metal, which is not used in forming the various elements of the substrates 100, from the die block assemblies. The die block assemblies also must be separated when three more of the substrates 100 are to be supplied to the die block assemblies for having elements cast therein.

20 The movable die block assembly 104 is reciprocated by rotation of a crankshaft 144 (see FIG. 55). The crankshaft 144 is rotated intermittently from a drive shaft 145 (see FIG. 57) of a drive unit 146, which is supported by the machine frame 108.

25 The drive unit 146 comprises an electric motor, a clutch, a brake, and a gear reduction unit. The clutch and brake operate at motor speed with the clutch held in engagement by a solenoid, which holds the brake disengaged. If the solenoid current is interrupted, a quick stop of the drive shaft 145 is produced since the brake is engaged and the clutch is disengaged simultaneously.

30 As shown in FIG. 62, the drive shaft 145, which is continuously rotated unless the brake in the drive unit 146 is engaged, drives a Geneva member 147 intermittently to cause intermittent rotation of the crankshaft 144. The Geneva driven member 147 is attached to a shaft 148, which is rotatably mounted on the machine frame 108. The shaft 148 has a gear 149 thereon for meshing with a gear 150 on the crankshaft 144. The diameter of the gear 149 is twice the diameter of the gear 150 so that 90° of rotation of the Geneva member 147 results in 180° of rotation of the crankshaft 144.

35 The drive shaft 145 has a pair of radial arms 151 and 152 mounted thereon for rotation therewith. The arm 151 has a roller 153 on its end, and the arm 152 has a roller 154 on its end.

40 The rollers 153 and 154 intermittently engage four radial slots 155, which are spaced 90° from each other, in the Geneva member 147. Thus, when one of the rollers 153 and 154 is disposed in one of the radial slots 155, the Geneva member 147 is rotated. However, since the slots are spaced 90° from each other, there is only rotation of the Geneva member 147 through 90° when one of the rollers 153 and 154 is engaged with one of the slots 155.

45 The drive shaft 145 has a pair of asymmetrically disposed arcuate lock members 156 and 157 attached thereto for intermittent engagement with equally angularly spaced arcuate lock surfaces 158 on the Geneva member 147. The surfaces 158 are disposed between the slots 155.

Since the arms 151 and 152 are disposed at an angle to each other whereby the rollers 153 and 154 are not diametrically disposed to each other, this arrangement provides a longer period (105°) during which the movable die block assemblies are open than the period (75°) during which the die block assemblies 104, 109, and 110 are closed as shown in FIG. 45. The open dwell position is shown in FIGS. 50 and 51.

The intermittently driven crankshaft 144 has a crank disc 159 (see FIG. 55) and a crank pin 161 eccentrically connected thereto for rotation therewith. A Pitman rod 160 has one end connected to the crank disc 159 by the crankpin 161. The other end of the Pitman rod 160 is connected to a rod 162, which has rollers 163 and 164 on its opposite ends. The roller 163 rides in a guide channel 165 on the machine frame 108 while the roller 164 rides in a guide channel 166 on the machine frame 108. Accordingly, as the crankshaft 144 is intermittently rotated, the rod 162 is intermittently reciprocated in a direction perpendicular to its axis.

The rod 162 is connected to the movable die block assembly 104 to cause reciprocation thereof when the rod 162 is reciprocated. The rod 162 has a pair of blocks 167 and 168 thereon and connected to rods 169 and 170, which are secured to the support member 113 (see FIG. 61) of the movable die block assembly 104. Thus, the intermittent drive of the crankshaft 144 results in movement of the movable die block assembly 104 in a reciprocating or lateral direction to move the die block assembly 104 toward and away from the die block assemblies 109 and 110.

The movable die block assembly 109 is continuously urged to the left by a pair of springs 171 and 172 (see FIGS. 57 and 59), which are mounted on reduced extensions of guideposts 173 and 174 (see FIG. 57), respectively. The guideposts 173 and 174 are supported by the die base 107.

The movement of the die block assembly 109 to the left by the springs 171 and 172 is limited by engagement of one side of a support block 174' of the die block assembly 109 with shoulders (one shown at 175 for the guidepost 173 in FIG. 59) on the guideposts 173 and 174 at their junctions with their reduced extensions. Accordingly, when the movable die block assembly 104 is moved to the left, the movable die block assembly 109 can follow the die block assembly 104 due to the urging force of the springs 171 and 172 until the movable die block assembly 109 engages the shoulders on the guideposts 173 and 174.

The movable die block assembly 110 is urged to the left by a spring 176 on the reduced extension 111 of the guidepost 105 and a spring 177 on the reduced extension 112 of the guidepost 106. The movement to the left by the springs 176 and 177 of the die block assembly 110 is limited by engagement of a surface of the die block assembly 110 with shoulders (one shown at 177' on the guidepost 105 in FIG. 59) at the junctions of the reduced extensions 111 and 112 of the guideposts 105 and 106. Thus, the die block assembly 110 ceases to follow the movement of the die block assembly 104 to the left when the shoulders on the guideposts 105 and 106 are engaged by the die block assembly 110.

Accordingly, when it is desired to open the casting apparatus of the present invention, the roller 154 (see FIG. 62) on the arm 152 must enter one of the slots 155 in the Geneva member 147. With the die block assemblies 104, 109, and 110 in the closed position, the initial rotation of the crankshaft 144 results in all of the die block assemblies 104, 109, and 110 moving to the left until the die block assembly 110 engages the shoulders on the guideposts 105 and 106 whereby movement of the die block assembly 110 to the left ceases as shown in FIG. 47.

Then, the further movement of the die block assemblies 104 and 109 to the left continues until the die block assembly 109 engages the shoulders on the guideposts 173 and 174. This stops further movement of the die block assembly 109 to the left; these positions of the die block assemblies are shown in FIG. 49. The complete movement of the die block assembly 104 to the left by the crankshaft 144 is shown in FIG. 50.

During the movement of the movable die block assemblies 104, 109, and 110 to the left, it is necessary to coordinate other movements therewith. Thus, it is necessary to shear the metal which is not used in forming the various elements on the substrates 100 from the remainder of the metal that forms the various elements on the substrates 100, to remove the substrates 100 from the movable die block assembly 104 by an unload arm 178 (see FIG. 55) to an unload chute 179, and to load additional of the substrates 100 within the movable die block assembly 104 by a load arm 180.

The preheated substrates 100 are supplied from feeding tracks 181-183 contained within a preheat oven extension of the enclosed housing 133'. Radiant electrical resistance elements 183' (see FIG. 57) disposed within the preheat oven extension of the enclosed housing 133' preheat the substrates 100.

The enclosed housing 133' maintains an atmosphere of inert or reducing gas enveloping the substrates 100 while they are being preheated in the feeding tracks 181-183. Suitable inert gases are nitrogen or argon. A suitable reducing gas is a mixture of 4 percent hydrogen with 96 percent nitrogen or argon, which is noncombustible in air.

An inert gas atmosphere may be used if there are no oxides on the metallization on the surfaces of the substrates 100 that would inhibit the bonding of die cast metal to the metallization. The inert gas atmosphere would then prevent the formation of oxides on the surface metallization of the substrates 100 while the substrates are being preheated.

A reducing gas atmosphere is used if there are oxides on the metallization on the surfaces of the substrates 100 that would inhibit the bonding of die cast metal to the metallization. The reducing gas atmosphere would then reduce the oxides to metal as well as prevent the formation of oxides on the surface metallization of the substrates 100 while the substrates are being preheated.

The load arm 180 picks up the preheated substrates 100 from the substrate feeding tracks 181-183. Thus, three of the substrates 100 are shown as having elements simultaneously cast therein by the present invention.

The shearing, movement of the unload arm 178, and movement of the load arm 180 are controlled by cams 184-187 (see FIG. 57), which are mounted on the drive shaft 145 for rotation therewith. Thus, the rotation of the cams 184-187 is synchronized with the lateral movement of the die block assemblies 104, 109, and 110.

The cam 184 controls the movement of the load arm 180 while the cam 187 governs the movement of the unload arm 178. The cams 185 and 186 regulate the movement of the metal feed gate section 115 of the movable die block assembly 109 and the die block 121 of the movable die block assembly 110 relative to the shearing sheets 116.

The cam 184 controls the position of the load arm 180 through positioning a load arm shaft 188, which has the load arm 180 fixed thereto and is slidably and rotatably supported by the die base 107 and the frame 108, in both an axial direction and a rotary direction. This is necessary to move the load arm 180 from the position of FIG. 55 to the position of FIG. 51 and then to the phantom line position of FIG. 52 to load the substrates 100 on the die block assembly 104 and then to return the load arm 180 to the position of FIG. 51 and then to the position of FIG. 55.

As shown in FIG. 63, the cam 184 has a near side cam track 189 and a far side cam track 190. The near side cam track 189 has a cam roller or follower 191 disposed therein.

The roller 191 is disposed on one end of a lever 192, which is pivotally mounted on a rod 193 carried by the frame 108. The other end of the lever 192 has a ball joint 194 thereon for connection to the lower end of a link 195 as shown in FIG. 58.

The upper end of the link 195 is connected through a ball joint 196 to a C-shaped lever 197, which is fixed to the load arm shaft 188. Accordingly, when the roller 191 enters the noncircular portion of the cam track 189, the load arm 188 is rotated in one direction. This moves the load arm from the position of FIG. 55 to the position of FIG. 51.

The cam 184 has a cam roller or follower 198 (see FIG. 63) disposed in the far side cam track 190. The roller 198 is disposed on one end of a lever 199, which is pivotally mounted on a rod 200 supported by the frame 108. The other end of the pivotally mounted lever 199 has a projecting stud 201 disposed in a stud engagement groove 202 in the load arm shaft 188. The cam track 190 is designed to move the load arm 188 axially so that the load arm 180 moves from the position of FIG. 51 to the phantom line position of FIG. 52 and vice versa. This same type of axial movement occurs when the load arm 180 is disposed adjacent the substrate feed tracks 181-183.

The cam 185 has a near side cam track 203 (see FIG. 57) and a far side cam track 204. The near side cam track 203 is utilized only for causing axial shear and/or ejection action such as that employed with the apparatus of FIG. 14. Therefore, the near side cam track 203 is not employed with the apparatus of FIGS. 45-52 and will not be described in detail herein. However, it should be understood that the near side cam track 203 has a roller 205 therein and attached to one end of a lever 206, which is pivoted on and supported by the rod 200. The other end of the lever 206 is connected to the shearing member 18. Thus, the near side cam track 203 is employed only with the apparatus used when the pulse transformer 38 is being formed.

The far side cam track 204 of the cam 185 has a roller 207 mounted therein and connected to one end of a lever 208, which is pivotally mounted on the rod 193 and has a ball joint 209 on its other end for connection to the lower end of a link 210. The upper end of the link 210 is connected through a ball joint 211 to a lever 212, which is fixed to a shearing eccentric shaft 213. Thus, the lever 212 rotates the shaft 213 through a limited arc of oscillation. The shaft 213 has an eccentric 214 (see FIG. 55) extending therefrom and disposed within a slot (not shown) in an extension 215 (see FIG. 59) in the metal feed gate section 115 and a slot (not shown) in an extension 217 (see FIG. 57) of the movable die block 121.

The cam 186 has a near side cam track 218 (see FIG. 57) and a far side cam track 219. The near side cam track 218 controls the position of a shear eccentric shaft 220 in the same manner as the far side cam track 204 of the cam 185 governs the shear eccentric shaft 213. The shear eccentric shaft 220 has an eccentric 221 (see FIGS. 55 and 59) extending through a slot 222 (see FIG. 59) in an extension 222' in the metal feed gate section 115 and a slot 223 in an extension 224 of the die block 121 of the movable die block assembly 110.

Accordingly, the eccentrics 214 and 221 cooperate together to move the movable metal feed gate section 115 of the die block assembly 109 and the die block 121 of the movable die block assembly 110 together in a vertical direction from the position of FIG. 45 to the position of FIG. 46 to shear metal feed gates 297' of a runner 297 from the heads of the pins 101 and 102 in the substrates 100. The eccentrics 214 and 221 rotate in the opposite direction sufficiently to return the gate section 115 and the die block 121 to the aligned position.

As shown in FIG. 59, the gate section 115 is mounted for sliding vertical movement within the movable die block assembly 109. Likewise, the die block 121 is mounted for sliding vertical movement in the die block assembly 110.

The extensions 217 and 224 of the die block 121 ride in vertically disposed guides provided between portions of support block 225 of the die block assembly 110 and retainer plates 226, which are secured to the support block 225 of the die block assembly 110 by screws. Similar retainer plates 227 are supported on the support block 174' of the die block assembly 109 by screws to cooperate with portions of the support block 174' to form vertically disposed guides for the extensions 215 and 222' of the gate section 115.

The far side cam track 219 of the cam 186 controls the position of a clamp actuation shaft 228, which has an eccentric 229 extending therefrom for cooperation with a clamp actuation bar 230. When the eccentric 229 engages the clamp actuation bar 230 and the shaft 228 is rotated, four-point locator

clamps 231, 232, and 233 (see FIG. 60) are moved to their open positions.

The far side cam track 219 of the cam 186 has a cam roller or follower 234 (see FIG. 57) disposed therein. The cam roller 234 is mounted on one end of a lever 235, which is pivotally mounted on the rod 193 and has a ball joint on its other end. The ball joint is connected to the lower end of a link, which has its upper end connected through a ball joint to an actuation lever 239 for the clamp actuation shaft 228 in the same manner as the connection between the levers 192 and 197. The actuation lever 239 is fixed to the clamp actuation shaft 228 so that the shaft 228 is rotated through a limited arc by cooperation between the far side cam track 219 and the cam roller 234. This is the same type of connection that rotates the load cam shaft 188.

The cam 187 has a near side cam track 240 and a far side cam track 241. The near side cam track 240 controls the movement in an axial direction of an unload arm shaft 242, which has the unload arm 178 fixed thereto and is slidably and rotatably supported by the die base 107 and the frame 108, while the far side cam track 241 controls the rotation of the unload arm shaft 242. Thus, the rotary and axial motion is imparted to the unload arm shaft 242 in the same manner as it is imparted to the load arm shaft 188. Therefore, a description of the connecting elements will not be described herein. The direction of rotation of the unload arm shaft 242 is opposite to that of the load arm shaft 188.

The four-point locator clamps 231-233 are employed to properly dispose each of the substrates 100 with respect to its die cavity. This insures that there is alignment between the openings in each of the substrates 100 and various cavities in the die block assemblies 104 and 109. Each of the four-point locator clamps 231, 232, and 233 is pivotally supported on the die sections 243, 244, and 245, respectively.

As previously mentioned, the four-point locator clamps 231-233 are actuated by movement of the clamp actuation bar 230, which is slidably supported by the die sections 243-245, by the eccentric 229. When the clamp actuation bar 230 is moved to the right (as viewed in FIG. 60) by the eccentric 229, stud projections 250, 251, and 252 engage slotted radial projections 253, 254, and 255 (see FIG. 61), respectively, of rotary rings 256, 257, and 258 (see FIG. 61), respectively.

The rotary rings 256-258 are mounted for rotation about the axes of the die inserts 247-249. The clockwise rotary motion, which is caused by movement of the clamp actuation bar 230 to the right, of the rings 256, 257, and 258 is opposed by springs 259, 260, and 261 (see FIG. 61), which act against slotted radial projections 262, 263, and 264 (see FIG. 61) of the rotary rings 256, 257, and 258, respectively. The slotted radial projections 262-264 are diametrically disposed to the slotted radial projections 253-255.

When the rotary rings 256-258 are rotated clockwise by movement of the bar 230 to the right (as viewed in FIG. 60), pins 265, 266, and 267, which are disposed between the slotted radial projections 253-255 and fixed to upper clamp levers 268, 269, and 270 of the four-point locator clamps 231-233, are moved therewith. As a result, the upper clamp levers 268-270 are pivoted counterclockwise about pivot pins 271, 272, and 273, respectively, on the die sections 243, 244, and 245, respectively.

This clockwise rotary motion of the rotary rings 256-258 by the movement of the actuation bar 230 to the right (as viewed in FIG. 60) also results in the counterclockwise pivoting of lower clamp levers (one shown at 275 for the clamp 232) for the four-point locator clamps 231-233 about pivot pins 277, 278, and 279. The lower clamp levers have pins 277', 278', and 279' fixed thereto and disposed between the slotted radial projections 262, 263, and 264, respectively.

Each of the upper clamp levers 268-270 of the clamps 231-233 has a clamp finger secured thereto for pivoting therewith, and each of the lower clamp levers of the four-point locator clamps 231-233 has a clamp finger secured thereto for

pivoting therewith. As shown in FIGS. 60 and 61, a clamp finger 280 is connected to the upper clamp lever 270 of the four-point locator clamp 233 by a screw 281. The clamp finger 280 also is pivotally mounted on the pivot pin 273 and has the pin 267 extending therethrough although not secured thereto.

The four-point locator clamp 233 has a lower clamp finger 282 fixed to its lower clamp lever by a screw 283. The lower clamp finger 282 also is pivotally mounted on the pin 279. The pin 279' also extends through the lower clamp finger 282 but is not secured thereto.

As shown in FIG. 60, the upper clamp finger 280 has contact pads 285 and 286 thereon for contacting the substrate 100 on two sides adjacent one of its corners. The upper clamp fingers of the four-point locator clamps 231 and 232 are similarly arranged.

The lower clamp finger 282 of the four-point locator clamp 232 has a pair of contact pads 287 and 288 thereon for engagement with the other two sides of the substrate 100 adjacent a corner, which is diagonally opposite the corner about which the contact pads 285 and 286 of the upper clamp finger 280 are located. The four-point locator clamps 231 and 232 have their lower clamp fingers similarly formed.

The geometry of each of the four-point locator clamps is arranged to accommodate and accurately center one of the normally sized substrates 100. The substrate is 0.455 inch square after it has been made by compacting and sintering from a mixture of alumina and glass powders. The shrinkage during sintering is a variable factor so that each of the substrates 100 has dimensional tolerances of ± 0.003 inch. Each of the four-point locator clamps 231-233 is required to accurately center one of the substrates 100, which may be as large as 0.458 inch square or as small as 0.452 inch square or any size therebetween.

The centering of the substrate 100 properly with respect to the axis of the die insert 249, for example, is accomplished through having a line, which extends from the center of the pin 273 to the centers of the pads 285 and 286, parallel to a line, which passes through the center of the pin 279 and the centers of the contact pads 287 and 288, with the lines being perpendicular to a line, which extends through diagonal corners of the substrate 100 and through the center of the axis of the die insert 249 when the substrate is 0.455 inch square. Slight differences between 0.455 inch and either 0.458 inch or 0.452 inch are such that the substrate 100 is still centered since the contact pads are moving along short arcs which approximate straight lines parallel to the substrate diagonal for these slight displacements.

If one of the substrates 100 should not be properly clamped between the clamp fingers of any of the four-point locator clamps or the substrate should be missing, the condition is sensed by the clamp fingers moving toward each other beyond their normal clamping position, and the drive unit 146 will be inactivated by having the solenoid current interrupted whereby the brake is engaged and the clutch disengaged. As shown in FIGS. 60 and 61 for the upper clamp finger 280 of the clamp 233, an extension 292 is disposed for actuating a button 293 of an electrical switch 294. When the button 293 is engaged by the extension 292, the solenoid current of the drive unit 146 is interrupted to stop rotation of the drive shaft 145. A similar arrangement exists for each of the four-point locator clamps 231 and 232.

When the unload arm 178 is disposed in the position of FIG. 55, a vacuum is being applied to the pockets (one for each of the three substrates 100) in the unload arm 178 through a flexible hose 295 to retain the substrates 100 in the pockets of the unload arm 178. With the unload arm 178 so disposed, the clamping fingers of the four-point locator clamps 231-233 are rotated clockwise to release the substrates 100. This is accomplished by the clamp actuation bar 230 being moved to the left (as viewed in FIG. 60) by the springs 259-261 due to the position of the eccentric 229. The springs 259-261 move the rotary rings 256-258 because of the position of the eccentric 229 with respect to the clamp actuation bar 230.

The unload arm 178 follows the leftward motion of the die block assembly 104 as the substrates 100 are ejected as shown in FIG. 50. The vacuum in the pockets of the unload arm 178 retains the substrates 100 as they are ejected.

5 Then, the unload arm 178 is moved axially away from the four-point locator clamps 231-233 and then rotated to direct the substrates 100 to the unload chute 179. When the unload arm 178 is disposed so that the unload chute 179 may receive the substrates 100, the vacuum is released from the pockets in 10 the unload arm 178, and pressurized gas is supplied to the pockets through the flexible hose 295 to direct the substrates 100 into the unload chute 179.

When the load arm 180 is disposed in the position of FIG. 55, a vacuum is applied to the pockets (one for each of the three substrates 100) of the load arm 180 by means of a flexible hose 296 to retain the preheated substrates 100 in the pockets of the load arm 180. The load arm 180 is then rotated and moved axially to a position in which the clamp fingers of the four-point locator clamps 231-233 may grasp the substrates 100. In this position of the load arm 180, the vacuum is released from the pockets of the load arm 180 and pressurized gas is applied to the pockets through the flexible hose 296 to urge the substrates 100 into engagement with the layers 114 of plastic on the die inserts 247-249.

15 The vertical runner cavities 131 and the horizontal runner cavity 132 have the runner 297 of solid phase metal therein. As shown in FIG. 47, the runner 297 includes the portions of the metal that were injected through the passages in the gate section 115 of the movable die block assembly 109 and form 20 the metal feed gates 297' of the runner 297. The shearing of the metal feed gates 297' in the gate section 115 from the heads of the pins 101 and 102 in each of the substrates 100 creates the runner 297, which has three vertical portions and a 25 connecting horizontal portion.

30 The runner 297 is retained within the die block 121 of the movable die block assembly 110 by hook ejector pins 300 when the die block assemblies 104 and 109 move to the left away from the die block assembly 110. The hook ejector pins 300 are retained in an ejector plate 301 by alignment pins 302.

35 The ejector plate 301 is urged to the right relative to the die block 121 by springs (one shown at 303 in FIG. 59) urging the ejector plate 301 against the heads of retaining screws (one shown at 304 in FIG. 59), which are secured to the die block 121. When the ejector plate 301 engages the heads of the retaining screws 304, the hook ejector pins 300 are disposed 40 as shown in FIG. 47.

45 As the die block assemblies 104 and 109 move to the left after the die block assembly 110 has ceased to move to the left because of engagement with the shoulders (one shown at 177' for the guidepost 105 in FIG. 59) on the guideposts 105 and 106, ejector actuation screws 305, which are secured to the die block 115 of the movable die block assembly 109 and have their heads acting against the ejector plate 301, pull the ejector plate 301 to the left against the force of the springs 303. As 50 a result, the runner 297 is removed from the die block 121 as shown in FIG. 48. After the runner 297 has been removed from the die block 121, a blast of high-pressure gas is supplied from a nozzle 307 to remove the solid phase metal runner 297 55 from the hooks of the ejector pins 300. Then, the runner 297 falls through the space between the movable die block assembly 109 and the die block assembly 110 as shown in FIG. 49.

60 The blast of high-pressure gas from the nozzle 307 is timed in accordance with the movement of the movable die block assembly 109. This insures that the pressurized gas is supplied at the desired time from the nozzle 307.

65 The timing of the blast of pressurized gas from the nozzle 307, the application of vacuums and pressurized gas to the pockets of the load arm 180 and the unload arm 178, the movement of the plunger 134, the actuation of the solenoid valve 129, and other timing sequences such as gas jets to clean and lubricate die cavities (not described herein) and additional safety sequences (not described herein) are controlled 70 from the drive unit 146.

As shown in FIG. 57, the drive shaft 145 of the drive unit 146 has a timing belt driving cog 310 mounted thereon for rotation therewith. The driving cog 310 is connected to a driven cog 311 by a timing belt 312 whereby the cog 311 is driven from the drive shaft 145.

The driven cog 311 is connected to a timer shaft 313 on which a plurality of timer cams 314 is mounted. Each of the timer cams 314 has a rise thereon to move a movable contact 316 of a switch 317 into engagement with a stationary contact to close an electrical circuit. Thus, each of these circuits controls one of the various timing relationships during the casting process of the present invention.

Considering the operation of the apparatus of FIGS. 45-52, the description of the operation will be started with the apparatus in the position of FIG. 45 in which the injection nozzle 130 is engaging the nozzle seat 122 but is not supplying liquid phase metal to the various cavities in the movable die block assemblies 104, 109, and 110. This is the position of 0° of the drive shaft 145 in the timing diagram of FIG. 56.

At this time, vacuum is being supplied by the vacuum pump 125 and all of the die assemblies 104, 109, and 110 are closed. The unload arm 178 and the load arm 180 are disposed adjacent the unload chute 179 and the substrate tracks 181-183, respectively. At this time, the pressurized gas is still supplied to the pockets of the unload arm 178 to direct the substrates 100 to the unload chute 179 but there is neither gas pressure nor a vacuum in the pockets of the load arm 180 at this time.

Shortly after rotation of the drive shaft 145 from 0°, the solenoid valve 129 is closed by means of one of the timer cams 314. At the same time that the solenoid valve 129 is moved to its closed position, the solenoid valve 142 is energized by another of the timer cams 314 to move the plunger 134 downwardly and supply liquid phase metal through the injection nozzle 130 to the various cavities within the die block assemblies 104, 109, and 110. During the time that the solenoid valve 129 is being closed and the solenoid valve 142 is being positioned to cause the plunger 134 to be moved downwardly, the unload arm 178 is moved axially away from the unload chute 179 and the gas pressure in the pockets in the unload arm 178 ceases.

When the solenoid valve 142 is again actuated to cause the plunger 134 to move upwardly to cease supplying of the liquid phase metal through the nozzle 130 to the cavities in the die block assemblies 104, 109, and 110, the load arm 180 is moved axially by the cam 184 to a position in which it can receive the preheated substrates 100 from the substrate feeding tracks 181-183. After the load arm 180 is positioned to receive the preheated substrates 100 from the substrate feeding tracks 181-183, vacuum is applied to the pockets of the load arm 180 through the flexible hose 296 to hold the substrates 100 on the load arm 180.

After the plunger 134 has been withdrawn upwardly, the die block assemblies 104, 109, and 110 are moved to the left by rotation of the crankshaft 144 to withdraw the nozzle 130 from communication with the ejection nozzle seat 122 in the die block 121 of the die block assembly 110 as shown in FIG. 46. In the position of FIG. 46, the movement of the die block assembly 110 to the left has stopped due to engagement of the support block 225 of the assembly 110 with the shoulders on the guideposts 105 and 106 as shown in FIG. 59.

As previously mentioned, the metal within the various die cavities solidifies as soon as friction ceases due to flow of the metal from the nozzle 130 stopping. Some of the metal may drain from the horizontal runner cavity 132 in the die block 121 to the nozzle 130.

Before the movement of the assembly 110 to the left is stopped, the gate section 115 of the movable die block assembly 109 and the die block 121 of the movable die block assembly 110 are moved vertically relative to the shearing sheets 116 whereby the heads of the interstitial pins 101 and the card pins 102 are sheared from the metal feed gates 297 along the same vertical line so that all of the pins on each of the substrates 100 have their upper surfaces in the same horizontal

75

plane when each of the substrates 100 is disposed in a horizontal plane. The vertical movement of the gate section 115 and the die block 121 is controlled by the eccentrics 214 and 221. This shearing is indicated in FIG. 56 by the term "shear pin gates."

The movement to the left of the movable die block assembly 110 ceases before the die block 121 and the gate section 115 return to the position in which the passages in the gate section 115 are aligned with the openings in the shearing sheets 116. Because of the length of the eccentrics 214 and 221 (see FIG. 59 for the length of the eccentric 221) and passages therefor in the die block assemblies 104, 109, and 110, the die block 121 and the gate section 115 may readily move to the left at the same time that they move vertically.

As shown in FIG. 56, the movable die block assembly 109 ceases its movement to the left at the same time that the gate section 115 and the die block 121 return to the position in which the passages in the gate section 115 are aligned with the openings in the shearing sheets 116. The movement of the die block assembly 109 to the left is stopped by engagement of surfaces on the support block 174' of the die block assembly 109 with the shoulders (one shown at 175 for the post 173 in FIG. 59) on the guideposts 173 and 174. This position of the die block assembly 109 is shown in FIG. 48.

As the movable die block assembly 109 moves to the left after the die block 121 ceases to move to the left, the ejector plate 301 starts to move to the left against the force of the springs 303 due to the ejector actuation screws 305. At this time, the ejector pins 300 urge the metallic runner 297 out of the die block 121 to the position of FIG. 48. The metallic runner 297 ceased to be supported within the passages in the gate section 115 when the movable die block assembly 109 continued to move to the left after the die block assembly was prevented from moving further to the left.

Prior to the time that the movable die block assembly 109 ceases to move to the left but after the die block assembly 110 stops moving to the left, the load arm 180 is moved away from the substrate feeding tracks 181-183 with the vacuum still applied to the pockets of the load arm 180. This retains the preheated substrates 100 in the pockets of the load arm 180.

Furthermore, when the die block assembly 110 ceases to move to the left, the unload arm 178 begins to rotate or swing to a position in which it can receive the substrates 100, which are clamped by the four-point locator clamps 231-233, when the clamps are moved to their open positions. The timing of the rotation of the unload arm 178 is such that it does not enter into the area in which the die block assemblies 104 and 109 are disposed until after the die block assembly 109 has ceased to move to the left.

After the die block assembly 109 has stopped moving to the left, the continued movement to the left of the die block assembly 104 creates a space therebetween as shown in FIG. 49. The unload arm 178 swings between the two die block assemblies 104 and 109 and is properly positioned adjacent the clamps 231-233 by the time that the clamps are opened by the bar 230. The unload arm 178 moves inwardly toward the clamps 231-233 during the time when the clamps are moving from a substrate retaining position to an open position to release the substrates 100.

However, even though the clamps 231-233 release the substrates 100, the substrates 100 are still retained within the cavities 118 in the die inserts 247-249 and the cavities 119 in the plastic layers 114 until an ejection plate 318, which is carried by the movable die block assembly 104, is unable to move to the left because of engagement with fixed ejection studs 319 extending from the die base 107. This occurs after the unload arm 178 has been positioned adjacent the substrates 100.

When the movable die block assembly 104 continues to move to the left with the ejection plate 318 abutting against the studs 319, ejection pins 320 on the plate 318 enter the die cavities 118 in the die inserts 247-249 to push the substrates 100 out of the die block assembly 104 through engagement of the ejection pins 320 with the bottoms of the card pins 102 of

the substrates 100. This breaks the frictional engagement of the card pins 102 with the die inserts 247-249 whereby the substrates 100 are no longer fixed to the movable die block assembly 104.

The ejection plate 318 is normally retained so that it does not move relative to the support member 113 of the movable die block assembly 104 through springs 321 (see FIGS. 59 and 61) urging the ejection plate 318 to the left against the heads of retaining screws (one shown at 322 in FIG. 61), which are fixed to the support member 113. In this normal position, the ejection pins 320 close the die cavities 118 to block off the ends of the die cavities 118 in the die inserts 247-249.

As the die block assembly 104 continues to move to the left, the now stationary ejection pins 320 and the now stationary substrates 100 remain in position while the unload arm 178 is moved axially to the left to receive the substrates 100 in the pockets of the unload arm 178. By the time that the unload arm 178 completes its axial movement toward the substrates 100, vacuum is applied to the pockets of the unload arm 178 to retain the released substrates 100 therein. When the movable die block assembly 104 completes its movement to the left, the substrates 100 will be held in the pockets of the unload arm 178 by the vacuum. This position of the movable die block assembly 104 and the position of the unload arm 178 is shown in FIG. 50 with the unload arm 178 already being moved axially away from the movable die block assembly 104.

The unload arm 178 starts to rotate after axial movement away from the movable die block assembly 104 has begun. This is to insure that there is no interference between the ejection pins 320 and the card pins 102 on the substrates 100.

When the unload arm 178 begins to move axially away from the movable die block assembly 104, the load arm 180 begins to rotate from its position adjacent the substrate feeding tracks 181-183 to a position adjacent the clamps 231-233 on the movable die block assembly 104. The load arm 180 moves into the position in which the substrates 100 thereon may be disposed for clamping by the clamps 231-233 on the movable die block assembly 104.

Before the load arm 180 completes its rotary movement, it begins to move axially toward the clamps 231-233. Upon completion of the axial movement of the load arm 180, the clamps 231-233 are moved into a clamping or retaining position by means of the eccentric 229 acting on the clamp actuating bar 230 on the clamp actuation shaft 228. This causes all of the substrates 100 on the load arm 180 to be held by the clamps 231-233.

During the time that the clamps 231-233 are being rotated from their open positions to their clamping positions, the vacuum in the pockets of the load arm 180 is released and gas pressure is applied to the pockets in the load arm 180 through the hose 296. This pushes the substrates 100 toward the clamps 231-233 so that the clamps 231-233 have full control of the substrates 100 for properly centering them before the clamps 231-233 complete the clamping movement.

At the time when the clamps 231-233 are holding the substrates and have completed their pivotal movement, the drive shaft 145 will have completed 270° of a revolution. At this time, the movable die block assembly 104 begins to move to the right due to rotation of the crankshaft 144 causing movement of the rods 169 and 170 in the opposite direction.

As the movable die block assembly 104 moves to the right, the load arm 180 rotates away from the space between the die block assemblies 104 and 109 so that the load arm 180 is out of the way of the movement of the die block assembly 104 b before it reaches the position in which it would engage the load arm 180. The load arm 180 continues to rotate until it is again positioned adjacent the substrate feeding tracks 181-183. It remains in this position for the remainder of the revolution of the drive shaft 145.

As the movable die block assembly 104 moves to the right, it engages the movable die block assembly 109 and causes it to begin to move to the right. Thus, the space between the die block assemblies 104 and 109 is now closed with the substrates 100 therebetween.

As the die block assemblies 104 and 109 continue to move to the right and before the die block assembly 109 engages the die block assembly 110, the unload arm 178 is moved axially to a position in which the substrates 100, which are supported therein, may be deposited in the unload chute 179. When the unload arm 178 is properly positioned, vacuum is removed from the pockets of the unload arm 178 and gas pressure applied thereto through the hose 295 to urge the substrates 100 into the unload chute 179.

As the movable die block assembly 104 moves to the right and before it engages the movable die block assembly 109, the ejection plate 318 returns to the position in which the ejection pins 320 are partially disposed within the cavities 118 of the die inserts 247-249. This is because the ejection plate 318 is removed away from the studs 319 so that the compression springs 321 urge the ejection plate 318 to the left until the ejection plate 318 engages against the heads of the retaining screws 322 to properly position the ejection pins 320 in the cavities 118 of the die inserts 247-249.

This proper position of the ejection pins 320 in the cavities 118 of the die inserts 247-249 is shown in FIG. 52. At this time, the load arm 180 will have been moved axially to the solid line position of FIG. 52.

With the substrates 100 supported between the movable die block assemblies 104 and 109 and the movable die block assemblies 104 and 109 continuing to move to the right, the solenoid valve 129 is opened to cause evacuation of the vacuum runner cavity 124, the vertical runner cavities 131, and the horizontal runner cavity 132 of the movable die block 121 by the time that the movable die block assembly 110 is engaged by the movable die block assembly 104 to begin to move the movable die block assembly 110 to the right. Before the movable die block assembly 109 engages the movable die block assembly 110, the ejection plate 301 will have returned to the position in which the pins 300 are properly positioned within the movable die block 121 rather than being disposed exterior thereof as shown in FIG. 48. Thus, the ejector pins 300 return to the position of FIG. 47 before the movable die block assembly 109 engages the movable die block assembly 110 to cause the movable die block assembly 110 to move to the right.

Upon the movable die block assembly 110 being engaged by the movable die block assembly 109 and moved to the right until the nozzle 130 is engaged by the seat 122, further rotation of the crankshaft 144 ceases at 360° of rotation of the drive shaft 145. At this time, the various elements of the apparatus are positioned as shown in FIG. 45, and another casting cycle continues in the manner previously described to cast the pins 101 and 102 in the substrates 100.

It should be noted that the gas blast nozzle 307 and pressurized gas flow through the hoses 295 and 296 are sources of the atmosphere of inert or reducing gas enveloping the die casting process and contained within the enclosed housing 133' as previously described.

Referring to FIGS. 17-19, there is shown another substrate 340, which is similar to the substrate 100. The substrate 340 has interstitial pins 341 die cast therein. However, corner card pins 342, which are formed with standoffs 343, and/or the interstitial pins 341 have their upper ends cast to provide a receptacle 344 having ears 345 on opposite sides thereof. The ears 345 serve to permit the liquid phase metal to flow from the cavity 131 in the die block 121 into the hole in the substrate 340. By utilizing the ears 345, all shearing may occur in the same plane, which is defined by the tops of the interstitial pins 341 and the tops of the ears 345.

Referring to FIG. 20, the substrate 340 is shown with a substrate 346 supported thereabove. The substrate 346 has stacking pins 347 cast therein by the die casting apparatus of FIGS. 45-52. The stacking pins 347 are formed so that their lower ends will be disposed within the receptacles 344 in the upper surfaces of the card pins 342 of the substrate 340. Accordingly, when the lower end of each of the stacking pins 347 is soldered to one or more of the corner card pins 342 and/or the interstitial pins 341, the substrate 346 is maintained in the desired stacked relation to the substrate 340.

Referring to FIG. 21, there is shown a substrate 350 having interstitial pins 351 and stacking pins 352, which also function as card pins, therein. The stacking pins 352 must be cast in two sequential casting processes. Thus, during the first process, the stacking pin 352 would only extend upwardly to the same height as the upper end of the interstitial pins 351 since this would be the shear line.

Then, the substrate 350 would be disposed in another casting apparatus wherein the remainder of each of the stacking pins 352 could be cast and bonded to the portion cast in the first of the sequential processes. The stacking pins 352 are formed with standoffs 353 to support a second substrate 354. Of course, each of the stacking pins 352 has a lower standoff 355, which functions to space the substrate 350 from the card.

The substrate 354 would rest on the shoulder of the standoff 353 of the stacking pin 352. The stacking pin 352 may be then soldered to circuit lines on the top or bottom surface of the substrate 354 to retain the substrate 354 thereon.

Alternately, the short interstitial pins 351 and the long card pins 353 may be cast in two sequential casting processes by first casting and shearing the short pins 351, but not the long pins 353, in the first casting process followed by casting and shearing the long pins 353 in the second casting process.

Referring to FIG. 22, the substrate 350 is shown as having a stacking pin 356 and the interstitial pin 341. The stacking pin 356 also is formed by two casting operations but the stacking pin 356 is shorter than the stacking pin 352. Each of the stacking pins 356 has a standoff 357 on its upper end to support the transformer 38, for example, solder connected and retained thereon.

Referring to FIG. 23, there is shown another product that may be produced by the method and apparatus of the present invention. A substrate 360 has card pins 361 cast therein simultaneously with a heat sink 362. The upper surface of the heat sink 362 and the pins 361 are in the same shearing plane. The die block assemblies 104 and 109 would be formed with appropriate cavities or recesses for the heat sink 362.

A radiating member 363, which also could be cast, is shown in phantom and would be attached to the heat sink 362 by stacking, for example. The radiating member 363 has fins to dissipate heat from the heat sink 362.

The method and apparatus of the present invention also may be employed to form circuit lines on a substrate such as substrate 370 (see FIGS. 24-26), which has the same properties as the substrate 100. The substrate 370 would have a thin metallized line 371 formed thereon by screening and firing in the well-known manner. The substrate 370 would then be preheated in an inert or reducing gas atmosphere to a bonding temperature, which is slightly below the melting point of the metal to be cast on the metallized line 371 by the die casting apparatus of the present invention.

The substrate 370 would next be disposed by suitable loading means within a die casting apparatus having cavities formed therein to produce an additional thickness of metal such as circuit line 372 on each of the metallized lines 371. The circuit line 372 is thereby bonded to the metallized line 371. It should be understood that the die cast metal may be fed to form the circuit lines 372 by connecting these die cavities to the pin forming cavities of FIGS. 17-22.

The preheating of the metallized substrates and the die cavities in an atmosphere of inert or reducing gas and subsequent evacuation of the gas from the cavities prior to die casting metal into the cavities promotes the bonding of the die cast metal to the metallized line 371 on the substrate 370 and also promotes the formation of the long circuit lines 372. Typical circuit lines such as the circuit line 372 may be produced 0.002 inch thick 0.004 inch wide, and over 1 inch long by the apparatus and process of this invention.

Thereafter, it would be necessary to remove any metal flashing of the circuit line 372 resulting from the die casting. This flashing could be removed by etching or grit blast, for example. If an etching were used, it would be necessary to rinse and dry the substrate 370.

Referring to FIGS. 27-30, there is shown another method in which the die casting apparatus of the present invention may be utilized to form and bond a circuit line on a substrate 380, which has the same properties as the substrate 100. As shown in FIG. 28, the substrate 380 may have its entire surface covered by a thin metallized layer 381, which forms an intermediate bond between the substrate 380 and the metal that is to be die cast by the apparatus of the present invention to form circuit lines 382 on the substrate 380.

10 The cavities of the die casting apparatus are arranged so that the circuit lines 382 are formed at the desired locations on the substrate 380. The apparatus and process are generally similar to those described for the substrate 370 except that after forming the circuit lines 382 on the substrate 380 through bonding the circuit lines 382 to the thin metallized layer 381, an etching process is utilized to remove the metal of the layer 381, which is not bonding the circuit line 382 to the substrate 380, and any flashing of the circuit lines 382.

15 Instead of removing the metal of the layer 381 after die casting the circuit lines 382 on the substrate 380, it should be understood that the metal of the layer 381 could be removed prior to die casting through a photoresist and etching process, for example. Likewise, instead of forming the cavities of the casting apparatus to produce only the circuit lines 382, the cavities could be formed so that the casting of the metal would occur over the entire surface of the metal 381. Then, by utilizing the photoresist and etching process, the circuit lines 382 could be formed through removing the remainder of the metal layer 381 and the remainder of the metal, which was die cast over the entire surface of the metal layer 381.

20 It should be understood that pattern fingers 385 (see FIG. 31) could be formed on a substrate 386, which has the same properties as the substrate 100, in the manner described for forming the circuit lines 372 or 382. The pattern fingers 385 are utilized to contact with balls or pads of chips, which are to be supported on the substrate 386.

25 Instead of using any of the foregoing means for bonding circuit lines and pattern fingers to a substrate, the circuit lines and pattern fingers could be retained on the substrate through mechanically anchoring the circuit lines and pattern fingers to interstitial pins and card pins, which would be mechanically retained in the substrate pin holes during casting. This type of arrangement is shown in FIGS. 32-36.

30 As shown in FIG. 36, a substrate 390, which has the same properties as the substrate 100, has a plurality of chips 391 supported on a surface thereof. The substrate 390 could have interstitial pins 392 (see FIGS. 32-34) and card pins 393 (see FIGS. 32 and 33), which have standoffs 394 thereon, cast therein in the manner previously described for the substrate 100.

35 The cavity of at least the die block assembly 109 would be formed so that circuit lines 395 and pattern fingers 396 would be cast integral with the pins 392 and 393. Thus, the circuit lines 395 and the pattern fingers 396 would be anchored to the substrate 390 by being mechanically connected to the pins 392 and 393. As shown in FIG. 32, each of the pattern fingers 396 has a ball or pad 397 of the chip 391 in contact therewith and bonded thereto.

40 Referring to FIGS. 40-42, there is shown a substrate 400, which has the same properties as the substrate 100, having interstitial pins 401 and card pins 402 cast therein by the apparatus of the present invention. Circuit lines 403 and pattern fingers 404 are cast and bonded on the upper surface of the substrate 400 in the same manner as previously described for the substrate 100.

45 Additionally, the lower surface of the substrate 400 has circuit lines 405 (see FIG. 42) cast therein by forming suitable cavities in the die block assembly 104. The circuit lines 405 would connect the pins 401 and 402 to a resistor 406, which has previously been formed on the lower surface of the substrate 400 by suitable means such as screening and firing, for example.

Referring to FIGS. 37-39, there is shown a substrate 410, which has the same properties as the substrate 100, having circuit lines 411 and pattern fingers 412 formed on its upper surface and isolated from any pins such as pin 413. Thus, the circuit lines 411 are utilized to connect various chips 414 to each other.

As shown in FIG. 39, the pin 413 is utilized to form circuit lines 415 on the bottom surface of the substrate 410. The only purpose of the pins 413 is to supply metal to cavities, which have been formed in the die block assembly 104, to cast the circuit lines 415 on the lower surface of the substrate 410. The circuit lines 415 connect resistors 416, which are on the lower surface of the substrate 410, to each other. The resistors 416 may be formed thereon in the same manner as the resistors 406 are formed on the substrate 400.

An advantage of this invention is that it reduces the cost for forming a pulse transformer through reducing the cost of both equipment and labor. Another advantage of this invention is that there is no damage to the core of the transformer during casting of the windings thereon. A further advantage of this invention is that it is readily adaptable to high-volume production of transformers. Still another advantage of this invention is that a large number of pins and connecting circuit lines may be formed simultaneously on a substrate without any fracture of the substrate. A still further advantage of this invention is that casting the various pins in a substrate permits more space for resistors, semiconductor devices, and the like.

While the invention has been particularly shown and described with reference to preferred embodiments thereof, it will be understood by those skilled in the art that the foregoing and other changes in form and details may be made therein without departing from the spirit and scope of the invention.

What is claimed is:

1. An apparatus for forming a casting comprising:
at least two mold members cooperating together to form a 35
mold cavity in a closed position;
means to effect relative movement between said mold members between opened and closed positions;
a third mold member
  - a. coextensive with selected one of said two mold members,
  - b. adapted for movement between coextending spaced and contiguous relationship with a portion of said one member, and
  - c. containing sprue channel portions in communicating 45
relationship with said mold cavity;
- means for effecting relative movement to said third mold member between said spaced and contiguous positions relative to said one member;
- means to introduce liquid phase metal through said sprue 50

channel portions into said cavities; and
means to move said third mold member in sliding and contiguous relationship parallel with said one member for sheering solidified sprue portions.

5 2. The apparatus of claim 1 including a fixed layer of resilient high-temperature plastic on the forming walls defining said mold cavity.

3. An apparatus for forming a casting comprising:
at least two mold members cooperating together to form a 10
mold cavity in a closed position;
means to effect relative movement to said mold members between opened and closed positions;

a third mold member

- a. coextensive with a portion of a selected one of two mold members,
- b. adapted for movement between coextending spaced and contiguous relationship with a portion of said one member, and
- c. containing sprue channel portions in a communicating 15
relationship with said mold cavity;

a fourth mold member

- a. coextensive with a portion of said third mold member,
- b. adapted for movement between coextending spaced and contiguous relationship with a portion of said third mold member; and
- c. containing second sprue channel portions in register 20
with and forming extensions of said first sprue portions of said third mold member;

means to move said third and fourth mold members in sliding relationship relative to each other in said contiguous position, to position said first and second sprue channel portions out of register with each other after chilling of said metal; and
means to introduce liquid phase metal through said second and first sprue channel portions into said mold cavity.

4. The apparatus of claim 3 for forming a casting including a 25
fixed layer of resilient high-temperature plastic on the forming walls of and defining said mold cavity.

5. The apparatus of claim 3 including:

means for effecting relative movement between said third mold member and said one mold member in sliding and contiguous relationship therebetween to change the relative position of said first sprue channel portions relative to said mold cavity after chilling of said metal to shear chilled sprue portions in said first sprue channel portions from the metal coextending to said mold cavity.

6. The apparatus of claim 5 for forming a casting including a 30
fixed layer of resilient high-temperature plastic on the forming walls of and defining said mold cavity.
